(57) **CLAIM**

The ornamental design for a decorative gun cabinet, as shown and described.

DESCRIPTION

FIG. 1 is a front elevational view of the decorative gun cabinet of the present invention;

FIG. 2 is a rear elevational view of the decorative gun cabinet of FIG. 1;

FIG. 3 is a left side elevational view of the decorative gun cabinet of FIG. 1, the right view being a mirror image thereof;

FIG. 4 is a top plan view of the decorative gun cabinet of FIG. 1; and,

FIG. 5 is a bottom plan view of the decorative gun cabinet of FIG. 1.

The broken lines showing of gun supports in the Figures are for illustrative purposes only and form no part of the claimed design.
